United States Patent

Des. 237,126
Patented Oct. 14, 1975

237,126

TABLE OR THE LIKE

Ronald J. McDonald, New Rochelle, N.Y.
(76-59 264th St., Floral Park, N.Y. 11004)

Division of design application Ser. No. 22,536, Apr. 20,
1970. Continuation of design applications Ser. No.
18,144, Ser. No. 18,145, Ser. No. 18,150, Ser. No.
18,151, Ser. No. 18,152, and Ser. No. 18,155, all filed
June 18, 1969, and Ser. No. 20,723, Dec. 31, 1969. This application Jan. 10, 1973, Ser. No. 322,528

Term of patent 14 years

Int. Cl. D6—03

U.S. Cl. D6—175

FIG. 1

FIG. 2

FIG. 3

FIG. 4

FIG. 5

FIG. 6

FIG. 7

FIG. 8

FIG. 1 is a perspective view of a table illustrating my design wherein the top is transparent and the base is opaque;

FIG. 2 is a plan view of the table of FIG. 1;

FIG. 3 is a longitudinal elevational view of the table of FIG. 1;

FIG. 4 is a transverse elevational view of the table of FIG. 1;

FIG. 5 is a perspective view of the table of FIG. 1 illustrating the appearance thereof with the top being opaque and the base being transparent;

FIG. 6 is a plan view of the table of FIG. 5;

FIG. 7 is a longitudinal elevational view of the table of FIG. 5; and

FIG. 8 is a transverse elevational view of the table of FIG. 5.

This is a divisional of application Ser. No. D. 22,536 filed Apr. 20, 1970 and a continuation of applications

D. 18,144, D. 18,145, D. 18,150, D. 18,151, D. 18,152 and D. 18,155, all filed June 18, 1969 and D. 20,723 filed Dec. 31, 1969.

I claim:

The ornamental design for a table or the like, as shown and described.
